UNITED STATES PATENT OFFICE

HAROLD J. REED, OF NASHUA, NEW HAMPSHIRE, AND CLAUDE L. SPAFFORD, OF SHERBROOKE, QUEBEC, CANADA, ASSIGNEES, BY MESNE ASSIGNMENTS, TO IMPROVED PAPER MACHINERY CORPORATION, OF NASHUA, NEW HAMPSHIRE, A CORPORATION OF MAINE

PNEUMATIC-CYLINDER MACHINE

Application filed June 4, 1927. Serial No. 196,621.

This invention relates to pneumatic cylinder machines intended for the extraction of liquid or moisture from material carried by the surface of the cylinder and consists in 5 improvements designed to render such machines more efficient and simpler in construction.

While the invention has application to various other arts and uses where it may be 10 desired to extract liquid from material in a more or less saturated condition or to subject material to filtration, the invention is herein shown for purposes of illustration as embodied in a pneumatic suction cylinder intended for use as a pneumatic decker or saw 15 all to remove water from pulp in paper manufacture where the pulp, supplied to a tank in a state of liquid suspension, is picked up in the form of a sheet by a partly submerged 20 cylinder, the water partly extracted therefrom and the sheet thereafter removed from the surface of the cylinder.

The invention will be best understood by reference to the following description when 25 taken in connection with the accompanying illustration of one specific embodiment thereof, while its scope will be more particularly pointed out in the appended claims.

In the drawings:

Fig. 1 is a central longitudinal sectional elevation showing a pneumatic cylinder machine embodying one form of the invention;

Fig. 2 is an end elevation of the machine 35 illustrated in Fig. 1 looking from the driving end thereof;

Fig. 3 is a plan view of the driving end of the machine showing the exposed end of the valve and the device for pressing it to its seat;

Fig. 4 is a side elevation of the distributing valve;

Fig. 5 is a sectional elevation taken through the cylinder and drum head on the line 5-5 in Fig. 1, looking in the direction of the arrow there indicated;

Fig. 6 is a detail, on a larger scale, in cross sectional elevation taken on the line 6-6 in Fig. 1 looking in the direction of the arrow there indicated and showing the relation of compartment partitions thereat; and

Fig. 7 is a sectional elevation, also on a larger scale, taken on the sectional line 7-7 in Fig. 1 near the opposite end of the compartment and looking in the direction of the arrow indicated in Fig. 1.

Referring to the drawings and to the illustrative embodiment of the invention therein shown, the cylinder, which is designated generally by the numeral 11, is mounted in suitable journal bearings 13 to rotate within the tank 14 to which the pulp is supplied in any suitable manner, as through an inlet 15 in the side walls of the tank. The stock is supplied in sufficient quantity to maintain the cylinder submerged to a point which may be indicated, merely by way of example, by the dotted line shown in Figs. 2 and 5. The cylinder is provided with a foraminous or porous surface, and the particles of fibre which tend to rise toward the top of the tank are picked up by the cylinder in its rotation, and, aided by a suction which is applied to successive compartments within the cylinder, the stock is carried upward in the shape of a web or sheet formed on the surface of the drum and at the same time a substantial measure of its moisture or liquid content is extracted. At some point in the rotation of the drum, the sheet, after being lifted from the liquid, is removed from the cylinder, its removal being assisted if desired by means of a doctor 16. To withdraw the waste water from the tank there is provided at the side of the tank an overflow trough or box 17 with a sloping bottom to which the waste water passes over a gate 18, the waste water being conducted away from the machine through the trough. The supply entering the tank through the inlet 15 is deflected downwards toward the opposite side 70 of the tank by the deflecting plate 19, and thence upwards by the oppositely arranged deflecting plate 20.

Referring to the cylinder, the latter is provided at opposite ends with hollow journals 95 21 and 23, the latter carrying the worm gear 25 through which a relatively slow rotation is imparted to the cylinder by means of the worm 27, the shaft 29 and driving pulley 31. Referring to the illustrative embodiment 100

of the invention, one end of the cylinder is provided with the end plate or head 33 secured to the journal 21 and the opposite end with an end plate or outer head 35, similar to the end plate 33, the plate 35 being secured to the hollow journal 23. Associated with the end plate 35 to form a drum head, there is provided a smaller flanged plate 37 connected to the end plate 35 by a series of radially arranged partition walls 39 (see Figs. 1 and 5) and constituting an inner head for the drum. To stiffen the structure, the end plate 33 is secured to the flanged plate 37 by one or more stiffening rods 41 and by the axial shaft 43 secured to the opposed hubs of the two end plates.

To control the application of fluid pressure or suction, as the case may be, to the various radially arranged compartments in the drum head, a sleeved valve-seat 45 is provided which fits the hollow journal 23 and protrudes into the drum head. The protruding portion of the sleeve is provided with circumferentially arranged ports 47 registering respectively with the bottoms of the said compartments, so that the protruding end of the sleeve forms a ported bottom wall for the various compartments of the drum head. The sleeve 45 has a closed inner end 49 which seats in a recess in the flanged plate 37, the sleeve being secured to the hollow journal to turn with the cylinder and the drum head.

Near their outer ends the radially arranged compartments communicate each with a longitudinally arranged compartment 51, the latter being relatively shallow and extending lengthwise the cylinder and the several longitudinal compartments being arranged in a series circumferentially about the periphery of the cylinder and localized near the periphery thereof.

These compartments, the construction of which is best seen from Figs. 1, 5, 6 and 7, are formed by the bottom plates 53 which are connected at one end of the shoulder 55 on the end plate 33 and at the opposite end to the edge of the flanged plate 37, the plates 53 sloping slightly toward the drum head so that each compartment has a gradually increasing depth in that direction. The sides of the compartments are formed by the radially arranged plates 57 which are secured (Fig. 6) at one end to small lugs 59 on the end plate 35 and also to the partition walls 39. At the opposite end they are secured (Fig. 7) to small lugs 61 on the end plate 33. At their outer ends the plates 57 are bent to incline in the direction of rotation of the drum to form the inclined sides 63, the sides 63 being secured to small lugs 65 on the end plate 35 and to similar lugs 67 on the end plate 33. The dividing side walls between the successive compartments are carried to the outer surface of the cylinder by means of the plates

69 overlapping the plates 63 and having their outer edges bent to extend radially outward substantially flush with the surface of the cylinder.

The surface of the cylinder is built up on a framework comprising a series of flat, circumferentially arranged rings 71, the plates 69 and 63 being grooved to receive the rings, and on the outer notched periphery of the rings there are laid a series of rods 73 extending lengthwise the cylinder. The cylinder frame as thus formed may be wound spirally with wire 75 and the porous or foraminous covering of the cylinder, which may consist of wire screen cloth, is laid on the foundation thus formed. This method of forming the outer foraminous surface of the cylinder is one commonly followed in the case of deckers or save-alls, but the porous or foraminous surface of the cylinder may be constructed in any other way desired and may be varied both as to material and construction to suit the particular purpose to which the machine is to be put.

As thus formed, the cylinder is provided with interiorly partitioned compartments isolated from each other in a pressure fluid sense, arranged circumferentially about the cylinder and covered by the foraminous surface thereof. These longitudinally extending compartments are localized near the periphery of the cylinder and are relatively shallow, while the radially arranged compartments with which they respectively communicate are localized at the end of the cylinder, so that the liquid which is extracted from the material on the surface of the cylinder after being drawn into the inner compartments is caused to travel in a substantially right angled path, first toward the end of the cylinder, and thence radially inward toward the axis of the drum head.

In connection with the valve hereinafter described, this avoids the use of deckles and provides a simple construction assuring absence of leakage. It also provides a compartment of relatively small cubical capacity, so that a pressure or vacuum can be quickly built up without the consequent lag, inaction and waste of energy which ordinarily accompany the rapid change or reversal of pressure condition in successive compartments of the rotating cylinder where compartments of relatively large cubical capacity are employed. The compactness of the compartments and their converging relation in the drum head also permit the use of a relatively small compact valve, reducing the cost of construction and providing a mechanically simplified arrangement.

In the operation of the machine provision is had whereby the compartments immediately adjacent to the cylinder surface which is being first submerged are connected to a special suction conduit which is separate from

the suction conduit used to take away the principal waste liquid. The portion of the cylinder where it first dips beneath the stock comes in contact with liquid richly charged 5 with the fibre and a substantial percentage of useful fibre is apt to pass through the cylinder with the waste water. By employing a separate suction conduit to be connected with the compartments successively passing 10 through this phase of the cylinder's rotation, this liquid may be separately withdrawn and, if desired, returned again to the stock.

The compartments which correspond to the 15 next angular phase of the cylinder's rotation, or those adjacent the cylinder surface which is fully submerged, are then connected with a suction conduit in which a relatively high vacuum is maintained and thereby become effective for laying the stock upon the cylinder, as well as withdrawing the liquid therefrom through the foraminous surface.

The compartments adjacent that portion 20 of the cylinder surface emerging from the liquid are next connected to a third and separate suction conduit which will further dry the stock, since it will not only extract further moisture therefrom but will draw a certain amount of air through the sheet and thereby further assist in drying the same.

Finally, as the stock approaches the delivery point, herein represented by the doctor blade 17, the compartments immediately preceding the same are subjected to fluid pressure so that the sheet is automatically 35 lifted from the surface and falls over the doctor blade.

To secure these results, we have provided 40 a sleeve valve 77 (Fig. 4) which extends from without through the hollow journal 23 and within the valve seat 47. The valve has the tapered shoulder 79 fitting a corresponding tapered surface of the bearing seat, and has also the ported end 81 which registers with the ported end of the valve seat 47 which is. 45 also tapered to seat against a correspondingly formed surface on the valve seat.

The outer flanged end of the valve is closed 50 by the cap plate 83 which is bolted thereto and the valve is held in fixed non-rotative position by means of the laterally extending lug 85 (see Figs. 2 and 3) which is jointed to the rod 87 anchored to the fixed bracket 89. The rod 87 is adjustable, however, so that the valve while held fixed may be adjusted within a limited range to different 55 angular positions.

In order to press the sleeve valve 77 yieldably against its seat, the cap plate 83 is engaged by a spring 91 which abuts against the 60 stationary yoke 93 which spans the cap plate and the worm gear 25 and is secured at its ends to the studs 95, the latter supported by brackets 97 which are fastened to the journal bearings 13. Each of the brackets 97 has a series 65 of openings so that the studs 95 may be set

in different positions to provide for different angular adjustments of the valve as effected by the adjustment of the rod 87.

The interior of the sleeve valve is sub-divided into several compartments by means of longitudinal partition walls, each compartment having a separate port opening at the ported end. These compartments comprise, first, a suction compartment 99 which communicates through the cap plate 83 with the suction conduit 101. At the opposite end of the valve the compartment 99 opens through the port 103 (see Fig. 4) and the ported valve seat into those compartments which are covered by the first submerged portions of the cylinder surface.

Next in order is the main suction compartment 105 which communicates with the main suction conduit 107 and opens through the port 109 and the ported valve seat into those compartments at the bottom of the cylinder corresponding to the portions of the cylinder surface most deeply submerged.

Next in order follows the suction compartment 111 connected with the separate suction conduit 113 and communicating through a port at the ported end of the valve and the ported valve seat with those compartments underlying that portion of the cylinder surface which is undergoing emergence from the liquid, as well as that portion which has emerged and occupies a position at the top of the cylinder.

Finally, a separate pressure fluid compartment 115 is provided connected to the conduit 117, the latter extending to a suitable source of pressure fluid supply and communicating at the ported end of the valve through the port 119 and the ported valve seat with the cylinder compartment or compartments which are in immediate approach to the doctor blade 17. The ported end of the valve is strengthened by a short longitudinal rib 120 which offers however no impediment to the free circulation of fluid throughout the compartment 105.

The pressure fluid compartment 115 is connected through a small end passage 121 with a pressure fluid space 123 (Fig. 1) formed between the end 49 of the hollow valve and the opposing end of the valve seat 47 so as to provide a balanced condition for the valve under the action of the fluid pressure in the compartment 115.

The angular relationship of the valve in 120 its normal position of adjustment to the different compartments and the action of the several suction conduits and the fluid pressure on successive cylinder compartments will be evident from Fig. 5 where the dotted line 125 indicates, by way of example, the level of the stock. Obviously, however, the level and the angular position of the valve may be varied within wide limits.

As the cylinder rotates in the direction of 130

the arrow shown in Fig. 5, the surface of the cylinder as it first submerges beneath the stock is subjected to the action of the vacuum in the suction compartment 99 and the stock is drawn against the surface yielding up its liquid content which is drawn through the surface of the cylinder into the longitudinal compartment 51, whence it passes through the corresponding radial compartment 39 and into the valve compartment 99 and out through the suction conduit 101. If sufficiently rich in good fibre it may be returned to the stock.

As the cylinder surface becomes further submerged it becomes subjected to the relatively high vacuum maintained through the valve compartment 105, the fibre suspended in the relatively more dilute portions of the stock at the bottom of the tank are also drawn against the cylinder surface and the water removed through the suction conduit 107 and diverted to the waste or white water outlet. As the cylinder surface reaches or approaches the point of emergence, the sheet or web formed on its surface is next subjected to the vacuum maintained through the valve compartment 111 and as it passes over the top of the cylinder continues to be subjected to such suction which not only further extracts the liquid from the stock thereon, but the drying action is accelerated by the air which is drawn into the compartments and passes out with the liquid through the separate suction conduit 113. The vacuum or suction maintained through the valve compartment 111 will normally be less than that maintained through the compartment 105 since the suction of the air through the stock will lower the vacuum.

Before the stock approaches the doctor blade it will have had the liquid quite effectively removed from it and the dry cake or sheet will then be automatically lifted from the surface of the cylinder by the fluid pressure which is applied beneath the same through the compartment or compartments just preceding its approach to the doctor blade, this taking place through the pressure compartment 115 of the valve and the valve port 119.

In referring to the radial compartments of the drum head and their radial arrangement, there is implied merely their general converging relationship toward the axis of the drum head since it is obviously not essential that there be any geometrically exact radial form or relationship for such compartments.

While we have herein disclosed and described for the purposes of illustration one specific embodiment of the invention, it is to be understood that the principles thereof may be adapted to other purposes than those herein described and that extensive deviations may be made from the form, relationship and mechanical construction of the parts

herein disclosed, all without departing from the spirit thereof.

Claims:

1. In a machine of the class described, a cylinder having a foraminous surface and provided with interior partitioned compartments extending lengthwise the same and arranged in series circumferentially about the periphery of the cylinder and covered by the foraminous surface thereof, means for rotating the cylinder partly submerged in relation to a supply of stock carried in liquid suspension, a source of pressure fluid supply, separate suction conduits, and a valve through which said compartments by the rotation of the cylinder are separately connected to the source of pressure fluid supply and the suction conduits, the compartments corresponding to the cylinder surface when first submerged being connected to one suction conduit, those corresponding to the fully submerged cylinder surface being connected to a second suction conduit, those corresponding to the cylinder surface immediately following emergence being connected to a third suction conduit, and those preceding the last named compartments being connected to the source of fluid pressure supply. 70

2. In a machine of the class described, a cylinder having a foraminous surface and provided with interior partitioned compartments extending lengthwise the same and arranged in series circumferentially about the periphery of the cylinder and covered by the foraminous surface thereof, means for rotating the cylinder partly submerged in relation to a supply of stock carried in liquid suspension, a source of pressure fluid supply, separate suction conduits, and a valve through which said compartments by the rotation of the cylinder are separately connected to the source of pressure fluid supply and the suction conduits, the compartments corresponding to the fully submerged cylinder surface being connected to one suction conduit, the preceding compartments corresponding to the cylinder surface immediately following emergence being connected to a second suction conduit, and those preceding the last named compartments being connected to the source of fluid pressure supply. 95

3. In a machine of the class described, a cylinder having a foraminous surface and provided with interior partitioned compartments extending lengthwise the same and arranged in series circumferentially about the periphery of the cylinder and covered by the foraminous surface thereof, means for rotating the cylinder partly submerged in relation to a supply of stock carried in liquid suspension, a source of pressure fluid supply, separate suction conduits, and a valve through which said compartments by the rotation of the cylinder are separately connected to the source of pressure fluid supply and the suction conduits, the compartments corresponding to the cylinder surface when first submerged being connected to one suction conduit, those corresponding to the fully submerged cylinder surface being connected to a second suction conduit, those corresponding to the cylinder surface immediately following emergence being connected to a third suction conduit, and those preceding the last named compartments being connected to the source of fluid pressure supply. 110

nected to the source of pressure fluid supply and the suction conduits, the compartments corresponding to the first submerged portion of the cylinder surface being connected to one suction conduit, the compartments corresponding to the cylinder surface immediately following emergence being connected to a separate suction conduit, and the preceding compartments following emergence and prior to submergence being connected to the source of pressure fluid supply.

4. In a machine of the class described, a cylinder having a foraminous surface and provided with interior partitioned compartments extending lengthwise the same and arranged in series circumferentially about the periphery of the cylinder and covered by the foraminous surface thereof, means for rotating the cylinder partly submerged in relation to a supply of stock carried in liquid suspension, separate suction conduits, and a valve through which said compartments by the rotation of the cylinder are separately connected to the suction conduits, the compartments corresponding to the cylinder surface when first submerged being connected to one suction conduit, those corresponding to the fully submerged cylinder surface being connected to a second suction conduit and those corresponding to the cylinder surface immediately following emergence being connected to a third suction conduit.

5. In a machine of the class described, a cylinder having a foraminous surface and provided with interior partitioned compartments extending lengthwise the same and arranged in series circumferentially about the periphery of the cylinder and covered by the foraminous surface thereof, means for rotating the cylinder partly submerged in relation to a supply of stock carried in liquid suspension, separate suction conduits, and a valve through which said compartments by the rotation of the cylinder are separately connected to the suction conduits, the compartments corresponding to the cylinder surface when first submerged being connected to one suction conduit and those corresponding to the fully submerged cylinder surface being connected to a second and separate suction conduit.

6. In a machine of the class described, a suction cylinder having a hollow journal and a foraminous surface, the cylinder being provided with a series of radially arranged compartments formed between inner and outer head walls of the cylinder and localized at an end of the cylinder, said compartments opening at their outer ends each into a relatively shallow compartment extending lengthwise the cylinder and covered by the foraminous surface of the cylinder, the inner ends of the radially arranged compartments being closed by a ported wall, a sleeve valve extending through the hollow journal of the

cylinder and controlling the suction on said compartments and a journal bearing for the cylinder independent of the valve.

7. In a machine of the class described, a suction cylinder having a hollow journal presenting a foraminous surface and provided with separate, interior, fluid compartments arranged in a series circumferentially about the periphery of the cylinder and covered by the foraminous surface thereof, each compartment being relatively shallow and extending lengthwise the cylinder with a slightly increasing depth toward one end thereof, a stock tank in which the cylinder is partly submerged, a head contained at the end of the cylinder comprising end plates and radial partitions providing a series of partitioned fluid compartments communicating respectively near the periphery of the cylinder with the longitudinal compartments and converging between said end plates toward the axis of the cylinder, a ported sleeve closing the bottom of said compartments, and a stationary sleeve valve extending through the hollow journal of the cylinder and partitioned to provide a plurality of fluid compartments adapted to be opened and closed with relation to said ported cylinder compartments and pressure fluid and suction connections for said valve.

8. In a machine of the class described, a suction cylinder having a hollow journal and a foraminous surface and having a plurality of compartments extending lengthwise the same, a stock tank in which the cylinder is partly submerged, a stationary hollow sleeve valve having longitudinal partitions sub-dividing it into a plurality of compartments and extending through the hollow journal of the cylinder, and a ported valve seat within the cylinder related to port openings in said valve whereby the cylinder compartments are connected in succession respectively to the compartments in said valve.

9. In a machine of the class described, a suction cylinder having a hollow journal and a foraminous surface and having a plurality of compartments extending lengthwise the same, a sleeve having a tapered seat with peripheral ports connected with said compartments, a stationary hollow valve having longitudinal partitions sub-dividing it with a plurality of compartments extending through the hollow journal of the cylinder and having a tapered end seating against the tapered ported sleeve and provided with port openings, said valve having a compartment connected to a source of pressure fluid supply, and one or more compartments with connections to suction conduits, said compartments being opened to the cylinder compartments in succession through said ports as the cylinder rotates.

10. In a machine of the class described, a suction cylinder having a centrally arranged

70

opening at one end, a foraminous surface, a plurality of compartments extending lengthwise the cylinder, a drum head with radial compartments communicating with said longitudinal compartments, a tapered valve seat carried by said drum head, a partitioned sleeve valve extending through said centrally arranged opening and having a tapered end seating against said tapered valve seat, and means outside the cylinder to yieldably press the valve to its seat.

11. In a machine of the class described, a suction cylinder having a circumferential series of liquid extracting compartments extending lengthwise the same, a drum head carrying radially arranged compartments, the outer ends of which communicate respectively with said longitudinal compartments, said drum head being formed between inner and outer head walls, a hollow valve extending through the journal of said cylinder, a hollow ported valve seat surrounding the valve and carried by said drum head and provided with ports communicating with said radially arranged compartments, said valve having a closed end confronting the inner wall of the drum head, means for pressing the valve inwardly to its seat, a pressure fluid compartment within said valve, and means for balancing the pressure fluid applied to the closed end of the valve.

12. In a machine of the class described, the combination with a suction cylinder having at one end a head provided with inner and outer head walls with radially arranged partitions to provide suction compartments, of a hollow, sleeved, valve-seat carried by said head having tapered valve seating walls and having port openings communicating with said compartments, and a hollow valve extending through the journal of the cylinder and into said valve-seat and having tapered walls seating against the tapered walls of said valve-seat.

45 13. In a machine of the class described, the combination with a suction cylinder having at one end a head provided with inner and outer head walls with radially arranged partitions to provide suction compartments, of a hollow, sleeved, valve-seat carried by said head having tapered valve seating walls and having port openings communicating with said compartments, a hollow valve extending through the journal of the cylinder and into said valve-seat and having tapered walls seating against the tapered walls of said valve-seat, and devices outside the cylinder to press the valve to its seat.

60 14. In a machine of the class described, a suction cylinder having a foraminous surface and a plurality of compartments extending lengthwise the same, a hollow tapered ported valve seat within and at one end of the cylinder, radial passages connecting the ports with said longitudinal compartments and a

hollow stationary valve extending through the end of said cylinder and having a tapered end seated against the tapered ported sleeve and a suction conduit connected to said hollow valve.

70 15. In a machine of the class described, a suction cylinder having a foraminous surface and a plurality of compartments extending lengthwise the same, a hollow journal extension at one end, an external journal bearing for said extension, a hollow ported stationary valve extending into said cylinder through said journal extension, passages communicating with said longitudinal compartments and controlled by said valve and means for angularly adjusting said valve.

75 16. In a machine of the class described, a suction cylinder having a foraminous surface and a plurality of compartments extending longitudinally the same, radial compartments at one end communicating with said longitudinal compartments and with a ported open-ended distributing space arranged centrally at one end of the cylinder, a coaxial distributing valve passing through the open end of the cylinder into the distributing space and controlling the opening and closing of the radial compartments and a journal bearing for the cylinder independent of said valve.

80 90 In testimony whereof, we have signed our names to this specification.
